Primary Examiner — Wan Laymon(57) **CLAIM**

The ornamental design for a personal assistance device, as shown and described.

DESCRIPTION

FIG. 1 is a top perspective view of a personal assistance device showing my new design;

FIG. 2 is a bottom perspective view thereof;

FIG. 3 is an exploded top perspective view thereof;

FIG. 4 is an exploded bottom perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken line showing protrusions and indentations in FIGS. 3 and 4 is included for the purpose of illustrating environmental structure and forms not part of the claimed design.

1 Claim, 10 Drawing Sheets(56)
